ABSTRACT OF THE DISCLOSURE

A logical circuit element comprises at least one field effect transistor of the metal oxide semiconductor (MOS) type. An input connected to a two-level-voltage D.C. supply is connected to its gate, and an input capacitor is series connected between the input and the source. For a first level the transistor is blocked, for the other it is unblocked. An output is connected to the drain. An output capacitor is series connected between the drain and the source. A pulse generator is connected to the output capacitor. It charges or not the output capacitor, according to the level of the voltage applied to the input. A diode prevents any discharge of the output capacitor across the MOS element.

The present invention relates to transistorized logical circuit elements.

According to the invention there is provided a logical circuit comprising at least one field effect transistor of the metal oxide semiconductor (MOS) type, having a source, a drain and a gate; an input for receiving signals connected to said gate, for blocking or unblocking said transistor; an input capacitor connected between said input and said source, and an output impedance connected in series between said source and said drain.

For a better understanding of the invention, reference will be made to the drawings accompanying the following description and in which:

FIG. 1 represents the basic element of a circuit according to the invention;

FIGS. 2 and 4 represent inverter elements;

FIGS. 3 and 5 are diagrams explaining FIGS. 2 and 4; FIGS. 6, 7, 8 and 9, show, respectively NOR, OR, AND and AND-NOT circuits according to the invention;

FIGS. 10 and 12 represent, respectively, two embodiments of transfer elements according to the invention;

FIG. 11 is an explanatory curve;

FIG. 13 shows an embodiment of a shift register according to the invention; and

FIG. 14 is a curve explaining FIG. 13.

FIG. 1 shows a field effect element with insulated gate of the type sometimes referred to as the MOS (metal oxide semiconductor) field effect transistor. The gate of the element is grounded through a capacitor C_1 .

The source-drain circuit is mounted in series with a capacitor C_2 , a diode D_1 and a pulse generator G .

The operation of the circuit is based on the following properties of MOS devices:

(a) The grid biasing consumes practically no energy, the grid leak being of the order of 10^{14} ohms. If a low capacitance capacitor C_1 is connected between gate and earth, the same will not be discharged after the disappearance of the gate voltage V_g . It holds the memory of the voltage V_g for a long period.

(b) The MOS element operates as an interrupter.

In the state corresponding to the presence of a given

gate voltage V_1 , the conductivity of the source-drain circuit is of the order of 1 millimho.

In the so-called "blocked" state, corresponding to the presence of a given gate voltage V_2 , the conductivity of the drain-source is reduced to 10^{-8} mho.

Thus, the operation of the arrangement of FIG. 1 is as follows:

It is assumed that the gate voltage V_g takes up the two values V_1 and V_2 , corresponding to the two states of a binary logic, voltage V_1 corresponding to the normal conduction and the voltage V_2 to the blocked state.

The generator G applying a short pulse to the terminals of capacitor C_2 , two cases have to be examined:

(a) The gate voltage is V_1 (capacitor C_1 charged to V_1). The MOS is conducting. The capacitor C_2 is charged through the source-drain circuit to the voltage V_2 (pulse amplitude). It will not discharge after the passage of the pulse, because the diode D_1 prevents any discharge.

(b) The gate voltage is V_2 (capacitor C_1 charged to V_2). The MOS does not conduct. The capacitor C_2 will not be charged.

Thus, once a pulse has been applied by generator G to the MOS element, there are two possible states of charge of the capacitor C_2 , which respectively correspond to the two states of charge of the capacitor C_1 . The information stored at the terminals of capacitor C_1 is thus transferred to the terminals of capacitor C_2 .

If $C_1=C_2=C$, the transfer of information has been effected with an expense of energy $W=CV_0^2$ with $V_0=V_1-V_2$, which is very small, and much lower than in transistorized multivibrators.

Naturally, C_2 may be replaced by an impedance Z . The same may comprise an element with binary memory X . By means of the arrangement of FIG. 1, the information may be transferred from C_1 to X .

FIG. 2 shows an inverter for a synchronous logical arrangement, derived from the diagram of FIG. 1.

In the following description, it will be assumed that the MOS elements are of the n-type. With p-type element, it is sufficient merely to reverse the sign of the voltages applied and the direction in which the diodes conduct.

V_1 will again designate the biasing voltage corresponding to the normal state, and V_2 the voltage corresponding to the blocked state.

FIG. 2 shows a "depletion" type MOS element. In other words, it is conducting for $V_1=0$ and blocked for $V_2=-V$.

A capacitor C_2 , a first generator of positive pulses 50 and a diode D_1 are connected, as indicated, in series in the source-drain circuit.

A second positive pulse generator 70, a negative source of D.C. voltage $-V$ and a diode D_2 are connected in parallel with the capacitor C_2 and the generator 50.

The gate circuit comprises a capacitor C_1 , whose terminal A_0 is connected to a fixed voltage source 80.

The transfer of information is effected from the point G_1 , where the grid potential is measured, to point G_2 , the output of the diode D_1 . The process is as follows:

With the capacitor C_2 discharged, the voltage $-V$ is applied at the point B_1 to the terminal of the diode D_2 .

At the moment T_1 (FIG. 3), a short positive pulse, whose crest is $+V$, is applied to the point A_1 by the generator 50. Two cases have to be considered:

(a) The potential at G_1 is zero, the MOS element is conducting, the capacitor C_2 is charged with the voltage $+V$. At the end of the pulse, the potential at A_1 becomes again zero; the voltage at G_2 is then equal to $-V$.

(b) The potential at G_1 is equal to $-V$, the MOS element is not conducting, the capacitor C_2 is not charged. At the end of the pulse, the potential at G_2 is zero.

The transfer of information from G_1 to G_2 takes place with changed sign.

A zero voltage at G_1 supplies $-V$ at G_2 .

$+V$ voltage at G_1 gives zero at G_2 .

The capacitor C_2 is discharged, when the generator 70 applies a positive pulse to B_1 .

FIG. 4 shows another embodiment of the invention. The MOS element is of the "enhancement" type, wherein the blocking voltage is zero and its conducting voltage is $+V$. The capacitor C_1 is mounted between the gate and earth. A diode D_1 is mounted in the source circuit and conducts in the direction from the source to point D .

A second diode D_2 is mounted in the drain circuit and conducts in the direction from the point A to the drain. Similarly, a third diode D_3 is mounted between the drain and the point B and conducts from the drain to point B . The capacitor C_2 is mounted between the drain and earth. The information is transmitted from the point G_1 (gate) to the point G_2 (drain).

FIG. 5 shows the voltages V_A , V_B , and V_D , which are respectively applied to points A , B and D , by pulse generators 90, 91, 92.

The operation of the circuit is as follows: the MOS element is blocked with zero gate potential and unblocked with a potential of $+V$.

The capacitor C_2 is discharged. A positive pulse, with a peak value equal to $+V$, is applied at the instant T_1 at point A , by pulse generator 90; since the point D is normally at a potential V applied by pulse generator 92, a negative pulse $-V$, synchronized with the former, reduce it to zero.

Two cases are possible:

(a) The potential at point G_1 is zero. The MOS element is not conducting. The pulse charges the capacitor C_2 through the diode D_1 to the potential V . $G_2=V$.

(b) The potential G_1 is equal to $+V$. The MOS element is conducting. The capacitor C_2 is short-circuited by a weak resistance (that of the MOS element) and is not charged: $G_2=0$.

The diode D_3 serves to discharge the capacitor C_2 at the end of the cycle by means of a negative pulse which is applied to point B at the time T_2 .

The elements according to the invention can be grouped in series or in parallel to build up various logical function circuits.

The input impedance of a MOS element is, in fact, formed by a very high resistance in parallel with a weak capacitance.

It follows that several inputs can be coupled in parallel.

Similarly, the output impedance of a blocked MOS element is very high and it is possible to connect without difficulty a large number of output circuits in parallel to a single capacitor.

FIG. 6 shows a circuit which is derived from the circuit shown in FIG. 2.

It comprises two elements MOS_1 and MOS_2 whose respective drain are connected to the diode D_1 and whose sources are connected to earth. Their gates are, respectively, connected to capacitors C_{11} , C_{21} . The two inputs are at points G_{11} , G_{21} . The diodes D_1 , D_2 and the capacitor C_2 are mounted as shown in FIG. 2. It suffices that one of the MOS elements should conduct, i.e., that points G_{11} or G_{21} should be at a zero potential to obtain $-V$ at point G_2 . The presence of the information 0 at one input results in the presence of this information 1 at the output.

FIG. 7 represents an OR circuit. This circuit is developed from that of FIG. 6 by adding a third circuit comprising an MOS_3 element, identical to that of FIG. 2. The pulse generators are 501, 701, 502, 702.

An information present at G_{11} or G_{21} is found at G_{21} , and can be made available at G_{22} .

FIG. 8 shows an AND circuit. The same consists of a circuit III such as that shown in FIG. 6, to the inputs of which are connected two circuits I and II, such as shown in FIG. 2.

The circuit of FIG. 9 is a NOR circuit. It comprises two elements MOS_1 and MOS_2 in series between earth and the diode D_1 .

The absence of information in the assembly prevents any conduction of the group MOS_1 , MOS_2 . Conduction takes place only if there is an information at the two elements.

FIG. 10 shows a so-called transfer element. It comprises an input G_1 and an output G_2 .

The input G_1 is connected to the gate of an MOS_1 element, the source of which is earthed. A diode D_1 is mounted in bridge circuit between the drain and the source. It conducts in the direction from the earth to the drain.

A capacitor C_2 connects the drain to the output G_2 . Two points A_1 and B_1 are connected between the point G_2 and a pulse generator 100 by two diodes; D_2 and D_3 , respectively. Diode D_2 is in the same direction as D_1 , diode D_3 in the opposite sense.

The operation of the arrangement may be understood with reference to FIG. 11, which is concerned with an "enhancement" type element.

Point A_1 is normally at zero potential and pulse source 100 applies thereto pulse with the crest $+V$ at the moment T_1 . Two cases may occur:

(a) At the moment T_1 , the potential of point G_1 is $+V$, and the MOS element is conducting. The capacitor C_2 is charged by the pulse passing through the diode D_2 , the capacitor C_1 and the MOS element. Point G_2 assumes the potential $+V$.

(b) The potential of G_1 is zero. The MOS element does not conduct. The capacitor C_2 is not charged. Its potential remains zero.

At the moment T_2 , a negative pulse discharges the capacitor C_2 . The diode D_1 fixes the potential of the armature of the capacitor C_1 , connected to the MOS element when the latter is blocked. This diode can be incorporated into the MOS element. In this case, it is formed by the junction between the drain and the body of the semiconductor.

In this drawing, an enhancement type element has been used. In the case of a depletion type element, it is sufficient to offset the voltage at A_1 and B_1 by a fixed value corresponding to the used element.

A modification is shown in FIG. 12. In this diagram, the diode D_1 has been replaced by an element MOS_2 , blocked during the positive pulse applied at A_1 and conducting during the remainder of the time. To this end, the gate of the element is connected to a point F held at a suitable potential. The source and the drain of the MOS_2 element are connected, respectively, to the source and to the drain of the MOS_1 element. Owing to the presence of the MOS_2 element, the input impedance of the unit, as seen from the point H , is low, which facilitates the setting up of a sequence of elements. If, in fact the junction point of two consecutive elements is at the point H , the danger of deterioration by leakage currents is eliminated.

It has thus been shown that, due to the circuits of FIGS. 10 and 12, the voltage at point G_1 is transported to point G_2 after the application of the control pulse. This is the reason why such circuits are designated as transfer circuits. They can be used in making shift registers.

The shift register of FIG. 13 comprises a number of stages, some of which are shown in FIG. 13 at M_p to M_{p+4} . Each of these stages is identical to the circuit shown in FIG. 10.

The output M_p of each of these stages is the input of the next stage.

A clock, not shown, supplies four distribution points A , B , and A' , B' .

The pulses for charging and discharging the capacitors C_p , C_{p+2} are delivered, respectively, by the points A , B . The pulses for charging and discharging the capacitors C_{p+1} and C_{p+3} are delivered by the points A' , B' , respectively.

The voltages at A, A', B, B' are represented in FIG. 14. The capacitors C_p , C_{p+2} are charged at the time T_1 , T_3 . The capacitors C_{p+1} , C_{p+3} are charged at the time T_2 , T_4 .

The discharges take place, respectively, at the time T'_1 , T'_3 and T'_2 , T'_4 .

The instants T_k and T'_k are offset in time by the width of one pulse. The control voltages of the register are recovered at the points M_p . . . . At the start, all voltages are zero, with the exception of one which is equal to V .

The voltage $+V$ progresses at every sequence of pulses of the clock from M_p to M_{p+1} .

Thus, at a given instant, only one gate is open, except during the switching periods.

Of course, the invention is not limited to the embodiments described and shown which were given solely by way of examples.

What is claimed, is:

1. A logical circuit element comprising at least one field effect transistor of the metal oxide semiconductor (MOS) type, having a source, a drain and a gate; an input for receiving signals connected to said gate, for blocking or unblocking said transistor; an input capacitor connected between said input and said source; an output terminal, means for connecting said output terminal to said drain, output capacitance means connected to said output terminal; a first pulse generator connected to said output capacitance means and a first diode in series between said drain and said source, for preventing the discharge of said output capacitance means across said MOS, when conducting.

2. A logical circuit as claimed in claim 1, wherein said output capacitance means is a capacitor.

3. A logical circuit element as claimed in claim 2, wherein said first diode is connected in series between said output terminal and said drain.

4. A logical circuit element as claimed in claim 3, further comprising means for connecting a source of voltage between said source and said input capacitor; a second positive pulse generator and a second diode for conducting said second positive pulses connected in series between a source of negative D.C. potential and said output terminal, said second positive pulses having the amplitude of said negative D.C. voltage.

5. A logical circuit element as claimed in claim 4, further comprising a second MOS transistor, having its drain source circuit connected in series to said source; said second MOS having a second input terminal, a second gate connected to said second input terminal, and a second input capacitor connected to said second gate, and means for connecting a second source of D.C. potential between said second input capacitor and said second source.

6. A logical circuit element as claimed in claim 2, wherein said first pulse generator and said first diode are series connected between said source and said drain, further comprising; a third pulse generator for generating third pulses of the same amplitude and of the opposite polarity to that of said first pulses, at the same instants as said first pulses, and a third diode for passing said third pulses to said source, and a fourth pulse generator for generating fourth pulses of the same polarity as said third pulses, and a fourth diode for passing said pulses to

said drain, said output capacitor being connected between said source and drain.

7. A logical circuit element as claimed in claim 2, wherein said output capacitor is series connected between said drain and said output terminal; an eleventh diode being connected between said drain and said source, for conducting the current between said source and said drain, a twelfth diode and said first diode being oppositely mounted, and connected to said output terminal; said first pulse generator and a twelfth pulse generator for generating pulses of a polarity opposite to that of said first pulses, being connected to said first diode and said twelfth diode respectively.

8. A logical circuit as claimed in claim 7, further comprising a second MOS having second drain and source parallelly connected with said drain and source of said first MOS, and a second gate, connected to a fixed potential.

9. A plurality of circuits as claimed in claim 8, cascade connected, the input terminal of one circuit being connected to the output terminal of the following one, and means for applying successive pulses to said input terminals of said circuits in succession.

10. A logical circuit element as claimed in claim 1 further comprising a second transistor having a second input terminal, a second gate connected to said second input terminal, a second input capacitor connected between said second gate and second source, a second drain connected to said drain and a second source connected to said source.

11. A logical circuit as claimed in claim 10, further comprising a third MOS transistor having a gate connected to said output terminal, a further output terminal, a source and a drain, a further output capacitor, a seventh positive pulse generator for applying seventh positive pulses to said further output capacitor, and a seventh diode, said seventh diode and said further capacitor being connected in series to said drain; an eighth pulse generator for applying eighth positive pulses to said further output terminal and an eighth diode for passing said last mentioned pulses.

12. A logical circuit as claimed in claim 10, further comprising a fifth and a fourth MOS transistor, having further respective input terminals and respective gates connected respectively to said further respective input terminals, a ninth positive pulse generator for applying positive pulses to said output capacitor, a ninth diode for passing said pulses to said source, a tenth positive pulse generator for applying pulses to said gate of said fifth and sixth MOS transistor, and a tenth diode for passing said pulses.
